Primary Examiner — John Windmuller*Assistant Examiner* — John R Yeh(74) *Attorney, Agent, or Firm* — Leydig, Voit & Mayer, Ltd.(57) **CLAIM**

The ornamental design for a string mop, as shown and described.

DESCRIPTION

FIG. 1 is a top, front, left perspective view of the string mop showing a first embodiment of my new design;

FIG. 2 is a top view thereof;

FIG. 3 is a bottom view thereof;

FIG. 4 is a left side view thereof;

FIG. 5 is a right side view thereof; and

FIG. 6 is a front view thereof.

FIG. 7 is a top, front, left perspective view of the string mop showing a second embodiment of my new design;

FIG. 8 is a top view thereof;

FIG. 9 is a bottom view thereof;

FIG. 10 is a left side view thereof;

FIG. 11 is a right side view thereof; and,

FIG. 12 is a front view thereof.

Stippling where present in the elongate string elements indicates a non-white color and in the elongate string elements where stippling is absent indicates a white color.
